UNITED STATES PATENT OFFICE.

BERNARD T. LEVEQUE, OF WENHAM, MASSACHUSETTS, ASSIGNOR TO UNITED SHOE MACHINERY CORPORATION, OF PATERSON, NEW JERSEY, A CORPORATION OF NEW JERSEY.

SEWING MACHINE.

Application filed January 31, 1925. Serial No. 6,041.

The present invention relates to sewing machines and more particularly to a needle guide mechanism for outsole lock stitch shoe sewing machines.

In certain types of lock stitch shoe sewing machines, as, for instances, the type of machine disclosed in the patent to Ashworth No. 1,169,909, it is customary to provide the needle guide with a thread guard to prevent the needle loop from catching on the needle guide as the loop is being passed around the bobbin case.

An object of the present invention is to provide a machine of the type requiring a thread guard for the needle guide with a needle guide having a cutting edge or edges to form a stitch receiving groove in the shoe sole and with a thread guard which will not interfere with the operation of the needle guide in forming the stitch receiving groove. With this object in view the present invention provides a thread guard which is maintained in position to prevent the needle loop from catching on the guide when the guide is in retracted position, but which is adapted for movement relative to the guide so as not to interfere with the formation of the stitch receiving groove when the guide is brought down upon the work. In the preferred form of the invention the thread guard is yieldingly mounted on the needle guide so that upon presentation to the work the guard may be held in engagement with the work while the groove cutter continues its movement to form the stitch receiving groove.

A further object of the invention is to provide a needle guide mechanism of improved construction and operation, and with this object in view the invention consists in certain novel features of construction, combinations and arrangements of parts hereinafter described and particularly defined in the claims.

In the accompanying drawings Fig. 1 is a side elevation of the preferred form of the invention with the needle and needle guide in retracted position; Fig. 2 is an elevation of the mechanism showing the arrangement of the parts when the needle guide is brought into engagement with the work; Figs. 3 and 4 are views similar to Figs. 1 and 2, showing the mechanism from the op-

posite side; Fig. 5 is a front elevation of the mechanism with the needle in retracted position; Fig. 6 is a detail front elevation showing the needle guide in engagement with the work; Fig. 7 is a plan view of a portion of the work showing a partially completed seam; and Fig. 8 is a sectional detail view of the portion of the work shown in Fig. 7. The illustrated embodiment of the invention comprises a work support 10, a curved hook needle 12, a needle carrier 14, and a needle carrier actuating bell crank 16, all of which are or may be of the general type disclosed in the patent to Ashworth above referred to. The needle passes through a needle guide 18 secured to a needle guide carrier 20, the needle guide being provided with cutters 22 on opposite sides of the needle for forming a stitch receiving groove in the work. The needle carrier and the needle guide carrier are provided with hubs 24 and 26 respectively, which are mounted for oscillatory movement upon a shaft 28. The needle carrier is oscillated by movement of the bell crank 16, and the movements of the needle carrier are transmitted to the needle guide carrier by means of a spring 30 having one end attached to a projection 32 of the needle carrier and the other end secured about a post 34 attached to the needle guide carrier, the spring being coiled about the axis of the hubs 24 and 26. This spring affords a yielding movement of the needle guide towards the work as the needle moves on a downward stroke, and the formation of the spring about the axis of the shaft permits the use of a sufficiently heavy spring to insure proper indentation of the work. Provision is made for positive retraction of the needle guide on an upward stroke of the needle through engagement of the projection 32 of the needle carrier with a boss 36 extending outwardly from the hub of the needle guide carrier.

Pivoted at 38 upon the needle guide carrier is a thread guard 40 consisting of a plate, the end portion of which extends above the needle guide 18 throughout the length of the latter in order to prevent entanglement of the loop of thread as it is passed about the bobbin case by the rotary hook of the machine. The opposite end of

the thread guard is connected by means of a light tension spring 42 with the post 34 of the needle guide carrier. The thread guard 40 is provided with an inwardly extending projection 44 which is adapted to abut against the surface of the needle guide and properly position the thread guard when the needle guide is in retracted position, as shown in Fig. 1. When the needle guide is oscillated toward the work, the thread guard comes into engagement with the work substantially simultaneously with the groove cutter 22, and during continued movement of the groove cutter to form the stitch receiving groove the thread guard is supported by the work, relative movement between the thread guard and the needle guide being permitted by virtue of the yielding connection between these parts. Upon retraction of the needle the needle guide is also retracted, and as the groove cutter moves away from engagement with the work the thread guard is urged by the spring 42 into its normal position for protecting the needle guide from catching the loop of thread, as shown in Fig. 1.

The nature and scope of the invention having been indicated and the preferred form of the invention having been specifically described, what is claimed is:

1. A lockstitch sewing machine having, in combination, stitch forming devices including a hook needle, a needle guide hav-

ing a cutting edge for forming a stitch receiving groove in the work, a thread guard for the needle guide, and means for mounting the thread guard to permit relative movement between the thread guard and the needle guide as the latter is presented to the work to perform the groove cutting opera- 40

2. A lockstitch sewing machine having, in combination, stitch forming devices including a hook needle, a needle guide having a cutting edge for forming a stitch receiving 45 groove in the work, a thread guard for the needle guide, and means for yieldingly mounting the thread guard with relation to the needle guide to permit indentation of the work by the cutting edge of the needle 50 guide without interference by the thread guard.

3. A lockstitch sewing machine having, in combination, stitch forming devices including a hook needle, a needle guide having 55 a cutting edge for forming a stitch receiving groove in the work, a thread guard pivoted on the needle guide, and a spring connecting the thread guard and the needle guide to permit relative movement between the 60 thread guard and needle guide as the latter performs the groove cutting operation.

In testimony whereof I have signed my name to this specification.

BERNARD T. LEVEQUE.
